CONTAINER

Reynolds, Guyer, St. Paul, Minn., assignor to
Waldorf Paper Products Company, St. Paul,
Minn., a corporation of Minnesota

Application January 11, 1943, Serial No. 471,947

6 Claims.

(Cl. 217—3)

My invention relates to an improvement in containers, and deals particularly with a type of box-like container to be used for storing and transporting liquid or semi-liquid materials.

Due to the present shortage of metal, there is a considerable need for containers formed of material other than metal. Such containers have several advantages. In the first place, they are often lighter than metallic containers and are not subject to corrosion or rusting. In the second place, non-metallic containers can often withstand shock without injury or leakage better than metallic containers.

It is the object of the present invention to provide a non-metallic container for containing liquid and semi-liquid materials which will hold the contents without leakage, and which may be subjected to considerable strain without injury.

An object of the present invention lies in the provision of a container having lining of a simple type which will not permit the seepage of liquid therefrom and which is so constructed that liquid can not be absorbed therewith.

It is a feature of the present invention to provide a container lining which is so arranged that no edge of the lining is in contact with the liquid within the container. The lining is so folded that the edges of the lining are out of contact with the liquid within the container. As a result this liquid can not be absorbed into the body of the lining through the edge thereof.

A further feature of the present invention lies in the provision of a container for holding liquid which includes a liquid proof lining of box-like shape to contain the liquid, and in the provision of non-metallic panels or frames to support and reinforce this lining.

An additional feature of the present invention lies in the fact that the box may be entirely disassembled after liquid has been shipped therein and the container may be returned in unassembled form. As a result, little space is required for the container when the same is returned to be refilled. The lining is so arranged that it may be discarded after each shipment and a new lining may be inserted each time liquid is shipped therein. An effective liquid-proof container for each shipment is thus insured.

These and other objects and novel features of my invention will be more clearly and fully set forth in the following specification and claims.

In the drawings forming a part of my specification:

Figure 1 is a perspective view of my container in readiness for shipment.

Figure 2 is a sectional view, the section being taken on a plane parallel to the bottom of the container.

Figure 3 is a sectional view through the container, the section being taken on a vertical plane through the side walls, top and bottom of the same.

Figure 4 is an enlarged sectional view through the vertical corner of the container.

Figure 5 is a transverse section through another vertical corner of the container.

Figure 6 is a section taken on a vertical plane through a lower corner of the container.

Figure 7 is a sectional view through a lining member folded in position to line the container.

Figure 8 is a plan of one side of the liner before the same has been folded.

Figure 9 is a transverse sectional view through the liner of a slightly different form of construction.

Figure 10 is a plan of one side panel of the liner shown in Figure 9 before the folding operation.

Figure 11 is the plan of another side wall of the container shown in Figure 9 before the folding operation.

Figure 12 is a transverse section through the wall liner of a slightly different form of construction.

Figure 13 is a plan view of the liner shown in Figure 12 before the same has been folded.

Figure 14 illustrates in perspective another modified form of box-liner.

Figure 15 is a plan view of the liner for the box top and bottom.

Figure 16 is a plan view of the liner before the same is folded.

Figure 17 is a perspective view of a box-corner, a portion of which is broken away to show the liner arrangement.

The container A includes a top 10, a bottom 11, and side walls 12, 13, 14, and 15. The walls 12, 13, 14, and 15, as well as the top and bottom, include in preferred form, a solid panel and a reinforcing frame thereon. For example, the side walls

include panels, such as 16, with a reinforcing frame 17 secured thereto for marginally reinforcing the same. The top 10 and bottom 11 preferably include panels 18 with a reinforcing frame

20 encircling the same. The specific construction

of these side walls is not important in the present invention.

The liner B for the container A forms the basis of the present invention and is the important feature thereof.

With particular reference to Figure 7 of the drawings, it will be noted that

the side walls of the container A may be lined by two separate lining elements 21, which cooperate to form a continuous inner lining. Each liner 21 includes a panel 22 which is connected along a fold line 23 to an anchoring flap 24. The panel 22 is connected along a parallel fold line 25 to an anchoring flange 26. This flange 26 is, in turn, connected along the fold line 27 to a panel 29 which is designed to extend along the inner surface of an adjacent wall. The panel 22 may, for example, form a liner for the side wall 15, while the panel 29 may form a liner for the panel 12. Similarly a panel 22 may form a liner for the panel 13, while the panel 29 may form a liner for the side wall 15. A liquid-proof adhesive or cement compound is inserted between the anchoring flange 26 and the adjacent marginal edge of the panel 29, this adhesive being indicated by the numeral 30 in Figure 5 of the drawings. A strip of adhesive, indicated by the numeral 31, is also applied between the anchoring flange 24 and the marginal edge of the free end of the panel 29. As a result the panels 22 and 29 are adhered in rectangular formation, as best indicated in Figure 2 of the drawings, with the anchoring flanges being positioned between the adjacent edges of the side walls 12, 13, 14, and 15 of the container.

The upper edge of each panel 22 is connected to an anchoring flange 32 along a fold line 33. A similar anchoring flange 34 is connected to the lower edge of the panel 22 along a fold line 35. These anchoring flanges 32 and 34 are folded outwardly at right angles to the panel 22 to extend over the upper and lower edges respectively of the side walls 13 and 15 of the container A.

The panel 29 is connected along the fold line 36 to an anchoring flange 37 and is also connected along a fold line 39 to an anchoring flange 40. The anchoring flanges 37 and 40 are designed to overlie the top and bottom edges respectively of the side walls 12 and 14 of the container A. The corners of the flanges 32, 34, 37 and 40 are mitered to fit together at the corners of the container. The mitered end 41 of the flange 37 fits in abutting relation to the mitered end 42 of the flange 32. Similarly the mitered end 43 of the flange 40 fits in abutting relation to the mitered end 44 of the anchoring flange 34. The mitered end 45 of the flange 32 fits into abutting relation with the mitered end 46 of the next adjacent liner element 21. Similarly the mitered end 47 of the flange 37 fits in abutting relation to the mitered end 49 of the next adjacent liner element 21. Thus along both the top and bottom edges of the side walls 12, 13, 14, and 15, the anchoring flanges form a continuous covering. The manner in which the anchoring flanges extend outwardly is illustrated in Figure 6 of the drawings. This figure shows the flange 34 folded outwardly to engage the lower edge of the side wall 15. A similar flange 32 extends beneath the side wall 13, while the flanges 40 extend beneath the side walls 12 and 14. The manner in which the mitered corners fit together is best indicated in Figure 7 of the drawings.

The top wall 10 of the container is lined by means of a flat liner sheet 50 extending throughout the entire area of this top. A liquid-proof adhesive is applied to the flanges 32 and 37 which overlie the side wall sections 12, 13, 14, and 15, and the top 10 with its liner is applied thereto. The adhesive secures the anchoring flanges 32 and 37 to the marginal edges of the top liner 50 and nails or other suitable fastening means 51

extend through the frame 20 of the top 10 and into the frames 17 of the various side walls. This not only holds the top 10 in place, but also secures the anchoring flanges 32 and 37 in engagement with the marginal edges of the top liner 50. The bottom of the container is similarly applied.

The bottom 11 is provided with a flat liner sheet 52 which extends coextensively with the bottom. An adhesive is applied to the exposed surfaces of the flanges 34 and 40 of the liner B, and the bottom 11 is adhered in place, the adhesive 53 adhering the liner 52 to the anchoring flanges 34 and 40. Nails 54 or other fastening means extend through the frame 20 of the bottom 11 and into the frame 17 of the side walls to hold the bottom in place.

In assembling the container it is usual practice to apply adhesive to the anchoring flanges 26 and to fold the liner along the fold lines 25 and 27 so that the anchoring flange 26 is firmly adhered to the inner surface of the panel 29. Each liner section 21 may then be assembled with its respective side walls 12, 13, 14, and 15 so that the flanges 32, 34, 37 and 40 overlie the upper and lower edges of the side walls. Adhesive is then applied to the anchoring flanges 24 and the two sections of the box are then adhered together. Fastening means, such as the nails 55, hold the two sections in proper relationship. Nails 56 have previously been used to connect the side walls 12 and 15 and to connect the side walls 13 and 14.

A box-shaped receptacle is thus formed and the bottom 11 is added, as has been described. The adhesive 53 is applied over the flanges 34 and 40 of the panels 22 and 29 and the bottom is placed in proper position and fastened by means of the nails 54.

A box is thus formed having an open top. The adhesive or cement is then preferably applied to all of the corners of the interior of the box so as to form a bead of cement or adhesive along each pair of connecting walls. The contents may then be placed within the container A and the top 10 applied by first coating the anchoring flanges 32 and 37 with cement and then placing the top 10 in position and fastening the same with the nails 51.

I have found that this container may be filled with oil and subjected to severe tests without leakage. Furthermore, the liquid within the container can not be absorbed into the material forming the liner, as there are no exposed edges on the interior of the container.

My container may likewise be lined with a liner indicated by the letter C in Figures 9, 10, and 11 of the drawings. The liner C includes four panels, two panels being of one pattern and the remaining two panels being of a slightly different pattern. The panels 61 are entirely flat throughout their width but are connected along the top edge by a fold line 59 to an anchoring flange 60 and are connected along their lower edge by a fold line 61 to an anchoring flange 62. The anchoring flanges 60 and 62 are designed to overlie the top and bottom edges of two exposed walls of the container, the panels 61 extending over the entire area of these two opposed side walls.

Panels 63 are designed to cover the other opposed walls of the container. The panels 63 are connected along a vertically extending fold line 64 to an anchoring flange 65 and are also connected along a fold line 66 to an anchoring flange 67. The panel 63 is connected along its upper edge by a fold line 69 to an anchoring flange 70

and along its lower edge 71 to an anchoring flange 12. The anchoring flanges 10 and 12, respectively, are designed to overlie the upper and lower edges of opposed side walls of the container. The anchoring flanges 65 and 67 are designed to fold at right angles to the panels 63 and extend along the vertical side edges of the opposed side walls of the container.

The method of securing the container together with the liner C is similar to the method previously described. In this case, however, the panels 57 are mounted upon two opposed side walls, while the panels 63 are mounted upon the other two opposed side walls. A mitered end 73 of the flange 60 extends in abutting relation to a mitered end 74 of the flange 70. The mitered end 75 of the flange 70 is designed to engage in abutting relation to the mitered end 76 of the adjacent flange 60. Similarly a mitered end 77 on the flange 62 is designed to abut against the mitered end 78 of the flange 72. The mitered end 80 of the flange 12 may abut against the mitered end 81 of the next adjacent flange 62. Thus, when the side walls of the container are assembled the mitered ends of the various panels engage in abutting relation and form a continuous marginal anchoring flange.

When the panels 57 and 63 have been assembled on their respective side walls an adhesive cement is applied to the anchoring flanges 65 and 67, and these flanges will adhere to the vertical marginal edges of the panels 57. Nails may be used to fasten the various side walls together, these nails extending through the anchoring flanges 65 and 67 and through the marginal edges of the panels 57. The top and bottom are identical to the top and bottom of the container A previously described and are similarly applied.

It should be noted that the liner C is identical to the liner B with the exception that the liner C is formed in two parts. In other words, the liner C corresponds to the liner B, if the liner B were cut along the fold line 27.

In Figures 12 and 13 of the drawings I disclose a liner D which may be used in place of the liner construction previously described. An examination of the liner D will show that this liner is identical to two liner sections 21 terminally connected together. In other words, in place of having two liner panels 21, a single elongated liner panel is formed which lines all of the side walls of the container.

The liner D includes a panel 81 connected along a fold line 82 to an anchoring flange 83. The anchoring flange 83 is connected along the fold line 84 to a panel 85. The panel 85 is connected along the fold line 86 to an anchoring flange 87. This flange 87 is connected along the fold line 88 to the panel 90. The panel 90 is connected along the fold line 91 to the anchoring flange 92. This flange 92 is in turn connected along the fold line 93 to the panel 94. The panel 94 is connected along the fold line 95 to the anchoring flange 96. The flange 96 is in practice adhered by a strip of adhesive 97 to a marginal edge of the first panel 81, thus connecting all of the panels in rectangular formation.

Adhesive is applied to the anchoring flanges 83, 87, 92, and 96 and these flanges are adhered to the adjacent vertical marginal edges of the panels 81 and 90. Two opposed side walls of the container extend coextensively with the panels 81 and 90 and the other two opposed side walls extend between the anchoring flanges 83 and 87, and between the flanges 92 and 96, respectively.

The side walls are connected in rectangular formation in the manner previously described.

Anchoring flanges 98, 99, 100, and 101 are connected along fold lines 102, 103, 104, and 105, respectively, to the upper edges of the panels 81, 85, 90, and 94. Similarly anchoring flanges 106, 107, 108, and 110 are connected along fold lines 111, 112, 113, and 114, respectively, to these panels. Mitered ends on these flanges provide connecting corners in abutting relation. The anchoring flanges at the top of the side walls are adhered to the top of the container, while the anchoring flanges at the lower ends of the panels are secured to the liner at the bottom of the container. The manner in which the top and bottom is applied has been previously described.

The liner E illustrated in perspective in Figure 14 of the drawings is formed as best illustrated in Figures 15 and 16. This liner includes a side wall panel 115 to which is connected along a vertical fold line 116, a sealing flap 117. The panel 115 is connected along a fold line 119 to a side wall panel 120 which in turn is connected along a parallel fold line 121 to a third side wall panel 122. This third side wall panel 122 is connected along the fold line 123 to the remaining side wall panel 124. A sealing flange 125 projects beyond the panel 124 so as to be secured to the sealing or anchoring flange 117 on the panel 115.

The panel 115 is provided with a top anchoring flange 126 and a bottom anchoring flange 127 connected to the panel along fold lines 129 and 130 respectively. The panel 120 is provided with a top anchoring flange 131 and a bottom anchoring flange 132 connected along parallel fold lines 133 and 134. The panel 122 is provided with anchoring flanges 135 and 136 connected to the panel 122 along fold lines 137 and 139. Similarly the panel 124 is provided with anchoring flanges 140 and 141 connected to the panel along fold lines 142 and 143, respectively.

The liner is arranged as best illustrated in Figure 14 of the drawings, the sealing or anchoring flange 117 being adhered with a liquid proof adhesive or cement to the flange 125. The top anchoring flanges 126, 131, 135, and 140 are bent outwardly from the side wall panels as illustrated, and the bottom anchoring flanges 127, 132, 136 and 141 are similarly bent outwardly. The top and bottom flanges overlie the top and bottom edges of the box side walls 12, 13, 14, and 15 in the manner which will be clearly understood.

The liners for the top and bottom of the box are shown, the top liner being indicated by the numeral 143, while the bottom liner is designated by the numeral 144. Both the top and bottom panels are identical in formation. The top panel 143 is provided with inturned corners 145 which are foldably connected to the liner along diagonally extending fold lines 146. The position of these fold lines is best illustrated in Figure 15 of the drawings. The fold lines 146 are so positioned that the inturned corners 145 fit snugly into the notches 147 between the adjacent top flanges at the corners of the liner. In other words, the liner 143 is adhered or otherwise affixed to the lower surface of the top panel 10 and the inturned corners 145 fit into the notches between the various anchoring flanges on the side walls. These inturned corners fill the space which would otherwise be uncovered and permits a flat even connection between the side walls and the top of the box throughout the entire area of the top liner.

The bottom liner 144 is provided with inturned corners 149 which are identical to the inturned

corners 145 on the liner 143. These inturned corners are folded along diagonal fold lines 150 which are placed in the same position as the fold lines 146. These inturned corners 149 fill the notches 151 between the adjacent ends of the anchoring flanges 127, 132, 136, and 141 and provide a solid connection between the various elements. The anchoring flaps or flanges may be adhered or cemented with liquid proof cement to the marginal edges of the liner 144.

In Figure 17 of the drawings, the relation between the inturned corners 149 and the anchoring flanges 127 and 132 is illustrated. As the top liner is of the same thickness as the side wall liner, the inturned corners act to double the thickness of the liner at the corners and to fill up the space within the notches 151 which otherwise might possibly permit some leakage.

It will be noted that there are no exposed edges in the liner to absorb moisture from the interior of the container, all of these edges being spaced from the contents of the container. The three liner constructions B, C, and D are extremely similar in form, and the only difference between these liners lies in the fact that where all of the panels are connected along fold lines they are somewhat easier to assemble than where each panel is separately formed. The liner B has been described first as this type of liner is not ordinarily too large to handle, while at the same time it is preferred to the separate panel construction shown as liner C. While the liner D, indicated in Figures 12 and 13 is preferable to either of the liners B or C, it is sometimes too long to handle readily when used for lining large containers.

It will be noted that after each shipment of liquid within the container A, the top 10, the bottom 11, and the sides 12, 13, 14, and 15 may be disassembled, and the liner discarded. The side walls may be returned to the shipper and the box may be reassembled using a new liner. Thus my container may be used for a number of shipments at a low cost.

The liners B, C, and D may be of any suitable material capable of accomplishing the desired result. Impregnated fibrous paper or board capable of withstanding liquids may be used. The liners are also preferably oil-proof and grease-proof, and may be provided with a protecting inner film, or may comprise a web of liquid-proof material.

In accordance with the patent statutes, I have described the principles of construction and operation of my container, and while I have endeavored to set forth the best embodiments thereof, I desire to have it understood that these are only illustrative of a means of carrying out my invention, and that obvious changes may be made within the scope of the following claims without departing from the spirit of my invention.

I claim:

1. A container comprising wooden side walls marginally connected together to form a tubular body, a liner including a panel overlying the inner surface of each side wall, the marginal side edges of each panel extending between the adjacent edges of said side walls, adhesive between the marginal panel edges, the bottom marginal edges of each panel extending to underlie the lower edges of said side walls, mitered corners on said bottom marginal edges, said mitered corners comprising acute angular notches having one side of the angle extending along the line of fold between said side panels and said bottom marginal edges, a wooden bottom closure having a liner overlying the inner surface thereof, and adhesive

between said bottom marginal edges of said panels and said liner overlying said bottom closure.

2. A container comprising wooden side walls marginally connected together to form a tubular body, a liner including a panel overlying the inner surface of each side wall, the marginal side edges of each panel extending between the adjacent edges of said side walls, adhesive between the marginal panel edges, the bottom marginal edges of each panel extending to underlie the lower edges of said side walls, mitered corners on said bottom marginal edges, said mitered corners comprising acute angular notches having one side of the angle extending along the line of fold between said side panels and said bottom marginal edges, a wooden bottom closure having a liner overlying the inner surface thereof, and adhesive between said bottom marginal edges of said panels and said liner overlying said bottom closure, the top marginal edges of said panels extending to overlie the top edges of said side walls, a wooden top closure, a liner overlying the inner surface of said top closure, and adhesive between said top marginal edges and said liner overlying said top closure.

3. A container comprising wooden side walls marginally connected together to form a tubular body, a liner including a panel overlying the inner surface of each side wall, the marginal side edges of each panel extending between the adjacent edges of said side walls, adhesive between the marginal panel edges, the bottom marginal edges of each panel extending to underlie the lower edges of said side walls, a wooden bottom closure having a liner overlying the inner surface thereof, and adhesive between said bottom marginal edges of said panels and said liner overlying said bottom closure, and mitered corners on said bottom marginal edges between said panels, said mitered corners extending in edge abutting relation along the bottom marginal edges of said side walls.

4. A container comprising wooden side walls marginally connected together to form a tubular body, a liner including a panel overlying the inner surface of each side wall, the marginal side edges of each panel extending between the adjacent edges of said side walls, adhesive between the marginal panel edges, the bottom marginal edges of each panel extending to underlie the lower edges of said side walls, a wooden bottom closure having a liner overlying the inner surface thereof, and adhesive between said bottom marginal edges of said panels and said liner overlying said bottom closure, the top marginal edges of said panels extending to overlie the top edges of said side walls, a wooden top closure, a liner overlying the inner surface of said top closure, and adhesive between said top marginal edges and said liner overlying said top closure, and mitered corners on said top and bottom marginal edges between said panels, said mitered corners extending in edge abutting relation along the bottom and top marginal edges of said side walls.

5. A box side wall liner comprising two sections, each section including a side wall panel, an anchoring flange connected thereto along a fold line, a second panel connected to said first anchoring flange along a fold line, and a second anchoring flange secured to said second panel along a fold line parallel to the first named fold lines, said second anchoring flange of each section being secured to the inner marginal surface of the first panel of the other section along the edge thereof opposite the first named fold line, bottom marginal edges on each panel extending outwardly

at substantially right angles to said panels, and mitered corners on said edges, said mitered corners extending in edge abutting relationship.

6. A box side wall liner including four panels, anchoring flanges connected by parallel fold lines between each adjacent pair of panels, said anchoring flanges being designed to fold flat along the surface of one of the panels to which they are connected, and an anchoring flange connected

5 by a fold line to an end panel designed to fold flat against the surface of the other end panel, bottom marginal edges on each panel extending outwardly at substantially right angles to said panels, and mitered corners on said edges, said mitered corners extending in edge abutting relationship.

REYNOLDS GUYER.
